ATTACHMENT FOR SPINNING MACHINES

Application filed September 1, 1927. Serial No. 216,990.

Our invention is an attachment whereby the ordinary doffing latch upon a spinning machine may be manipulated to secure the ring rail in position for forming a bunch. 5 There has been heretofore provided upon spinning machines a doffing latch carried by the lifter arm and so arranged that, when doffing was required, the ring rail may be held at the lowest limit of its travel but this doffing 10 latch was ineffective to permit the formation of bunches in an economical manner, and we have devised a very simple and inexpensive attachment for the doffing latch by the use of which the ring rail may be held in proper 15 position to permit the formation of a bunch without waste of yarn. The invention is illustrated in the accompanying drawing and consists in certain novel features which will be particularly pointed out in the claims following a detailed description.

In the drawing:

Figure 1 is a front elevation of a portion of a spinning machine having our invention applied thereto and showing the parts in the 25 doffing position;

Fig. 2 is a detail elevation showing the latch in the normal position to permit the usual operation of the spinning machine;

Fig. 3 is a detail perspective view of the 30 device constituting our invention;

Fig. 4 is an enlarged detail perspective view of the doffing latch, and

Fig. 5 is a detail perspective view of the bunch latch and the doffer latch assembled.

35 Referring particularly to the drawing, the reference numeral 1 indicates the ring rail, 2 the spindle rail and 3 the lower rail which are of the usual construction, the ring rail carrying the rings, indicated at 4, and the 40 spindle rail carrying the spindles, indicated at 5, in the usual manner, the spindle rail and the lower rail being fixed to the frame of the machine and the ring rail being mounted for vertical reciprocation. The ring rail

45 is supported upon a series of lifter rods 6 which have their upper ends in engagement with the under side of the rail and their lower ends engaged with lifter arms 7 which are equipped with counter-weights 8 and also 50 have upwardly projecting arms 9 connected

with the builder mechanism (not shown) in the usual manner. The builder mechanism, in the ordinary operation of the machine, exerts a pull upon the arm 9 so that the lifter arm 7 is depressed against the force of the counter-weight 8 and the ring rail is thereby permitted to descend under its own weight while return movement is effected by the counter-weight when the low part of the builder cam is presented to the member co-operating therewith. Pivotaly mounted upon the free end of the lifter arm is a doffer latch 10 which is constructed with a step 11 at its lower extremity immediately adjacent its pivotal connection with the lifter arm and has its upper extremity in the form of a shoulder 12 adapted to engage under the rail 3 of the frame so that the upward movement of the lifter arm and the lifter rod 6 engaged thereby will be prevented, the ring rail being thus held in its lowest position so that doffing may be effected. Normally, the doffing latch lies to one side of the lifter arm so that it will clear the lower rail 3 and move vertically past the same, as will be understood on reference to Fig. 2, but when doffing is to be effected the operator presses upon the step 11 and thereby swings the doffing latch into the vertical plane of the rail 3 so that upon the ensuing upward movement of the lifter arm the shoulder 12 will engage under the rail and restrain the upward movement of the ring rail. In order that the latch may be adjusted to various requirements, it is constructed in two members, as shown clearly in the drawing, having interengaging teeth, indicated at 13, and one member having a longitudinal slot 14 to receive a clamping bolt, indicated at 15, carried by the other member.

90 All of the parts so far described are well known in the art and operate in the well known manner which has been briefly outlined. The latch shown and described, however, was ineffective to hold the ring rail in the bunch-forming position and bunches formed upon the spindles in machines equipped only with the described doffing latch caused a very pronounced waste of yarn. To minimize the waste and provide means whereby the ring 95 100

rail may be held in the bunch-forming position, we have devised the bunch latch shown in Fig. 3 and consisting of a somewhat vertically elongated block 16 provided on one side face with the parallel flanges or edge ribs 17 adapted to engage closely to the side edges of the upper member of the doffing latch, the forward flange being beveled off at the upper end, as indicated at 18, whereby it may fit closely to the inclined offset web 19 on the doffing latch. The side face of the bunch latch is also beveled, as indicated at 20 to permit the bunch latch to be fitted closely to the doffing latch and be secured firmly to the latter by the bolt 15 which is inserted through a longitudinal slot 21 formed in the lower portion of the bunch latch in an obvious manner. Immediately adjacent the upper end of the bunch latch on the forward edge of the same, there is formed a stop or offset 22 presenting a shoulder which is located below the shoulder 12 of the doffing latch and is adapted to engage the frame rail 3 when the ring rail is in a somewhat higher position than that in which it will be held by the doffing latch, thereby holding the ring rail at rest in the bunch-forming position.

The bunch latch is secured rigidly to the doffing latch and operates with it and may be adjusted vertically with the upper member of the doffing latch so that the stop or shoulder 22 of the bunch latch will always occupy the same position relative to the shoulder 12 of the doffing latch. When doffing is to be effected, the device is operated in the stated manner so as to engage the doffing latch under the lower rail 3 and the ring rail will then be held in its lowest position until the rotation of the builder cam presents another high part thereof to the member cooperating therewith, whereupon the latch will be released in the usual manner. When a bunch is to be formed, the operator depresses the lifter arm in the same manner as for doffing but to a less degree so as to permit the offset or shoulder 22 to engage under the rail 3 thereby holding the ring rail at a higher point and permitting the formation of a bunch.

Our device is obviously simple and inexpensive and actual tests thereof have demonstrated that it is efficient in use and effects a very pronounced saving in the ends of the yarn.

Having thus described the invention, we claim:

1. In a spinning machine, the combination with a doffing latch, of a bunch latch consisting of a block having side flanges engaging the side edges of the doffing latch and equipped on its front edge adjacent its upper end with a rail-engaging shoulder disposed below the rail-engaging element of the doffing latch, and means for securing the bunch latch rigidly to the doffing latch.
2. In a spinning machine, the combination

with a doffing latch, of a bunch latch consisting of a block adapted to fit against the side of the doffing latch and having parallel flanges engaging the front and rear side edges of the doffing latch and having its side face at its upper end beveled and having an offset on its front edge adjacent its upper end to engage a rail of the spinning machine frame, the block being further provided with a central vertical slot, and a securing bolt inserted through said slot and through the doffing latch whereby the bunch latch may be rigidly secured to the doffing latch and adjusted with the latter.

In testimony whereof we affix our signatures.

ALEXANDER B. SUMMEY. [L. S.]
